METHOD OF MODULATION

Hans Roder, Scotia, N. Y., assignor to Telefunken
Gesellschaft für Drahtlose Telegraphie m. b. H.,
Berlin, Germany, a corporation of Germany

Application October 3, 1930, Serial No. 486,134.
Renewed July 28, 1933. In Germany October
9, 1929

10 Claims. (Cl. 179—171)

If a telephony transmitter is to fulfill the demand of insuring undistorted transmission of music, voice, etc., it should be modulated only inside the straight portion of the modulation curve. 5 However, in practice this curve usually departs from a straight line rather appreciably even when the modulation is only around 50% and is more marked as the modulation increases. Thus, if one confines oneself to this range, the energy 10 which is radiated is utilized rather poorly, a condition quite distinct from telegraphic transmitter stations which are operable at 100%.

Now, according to this invention modulation up to 100% is to be made feasible also for telephony 15 transmitter or broadcast stations without an incidental impairment in quality of the transmission being caused, by that the output potential of the microphone amplifier is so distorted in a suitable manner that as a result such distortions as are due 20 to the modulation curve will be compensated. Now, for such artificial distortion intended to be used for compensation, there may be employed the lower knee of the characteristic curve of a triode tube. Several circuits arranged to practice this 25 idea are shown by way of example in the several figures in the drawing. In these circuits of the several figures like reference characters indicate like parts.

Figure 1 shows a circuit in which modulating 30 potentials are applied by way of a modulating tube and circuit including the novel features of the present invention to the input circuit of an oscillation repeater tube;

Figures 2 and 3 are curves illustrating the manner 35 in which distortion is corrected by the use of the novel features of this invention;

Figures 4, 5 and 7 show modifications of the arrangement of Figure 1. The circuit of Figure 4 is especially applicable to modulation schemes of the 40 Heising type;

Figure 6 is a curve illustrating the operation of the modulating circuit illustrated in Figure 7; while,

Figures 8 and 9 are curves showing the relation 45 between currents in certain portions of the circuits of the modulating systems.

In describing the invention reference will first be made to Figure 1. In Figure 1 the carrier frequency repeater 2 has an alternating current 50 source connected therewith through a transformer 3, the secondary winding of which is connected with a grid electrode 5 and cathode 7 of the tube II. The carrier frequency impressed on 3 is repeated in 5 and modulated at signal frequency 55 therein. The modulating potential e_1 is applied

to the grid of modulating signal amplifier tube I in series with a negative grid electromotive force E_g . In parallel relation to e_1 is a voltage divider 4. In the plate circuit of tube I is an electromotive force E_a in series with a resistance e_r . The grid potential e_{gm} is obtained at the terminals ab and XY and is applied to the modulator tube II. In the presence of negative or low positive values of e_1 (as grid biasing potential of I), $e_{gm}=e'_1$ and is directly proportional to e_1 (in reversed polarity). That is, the polarity of the modulating potentials applied to the input electrodes of the tube II will be reversed with respect to the potential applied to the input electrodes of tube I. The potential e_{gm} is the sum of e'_1 plus any drop in e_r resulting from current flowing in the output circuit of tube I. When e_1 is small the drop through e_r is negligible and e_{gm} equals e'_1 . As the positive values of e_1 grow, there becomes added to e'_1 a potential drop occurring across the plate resistance e_r of tube I. This potential drop increases at more than the linear rate with respect to the applied potential e_1 and the result is that e_{gm} increases now more markedly than in direct proportion to e_1 . This increased potential at e_{gm} compensates for the normal distortion applied to the modulating signal by the modulator tube. 20 25

The manner in which this distortion applied to the modulating potential in the anode of the modulation amplifier I corrects the distortion 30 inherent in modulating systems known hereinbefore will be better understood by reference to Figures 8 and 9 of the drawing.

In Figure 8 the amplitude of the modulated output of a repeater, as, for example, repeater 2, is 35 plotted as the ordinates against the audio frequency input, which may be applied without distortion to the input electrodes of tube II, the latter being plotted along the abscissae axis. As will be seen, the relation between the applied potentials 40 and the modulations on the carrier is not linear.

In Figure 9 the ordinates are again the amplitude of the modulated output of tube 2, but here it is assumed that the audio frequency input is applied at e_1 so that they are distorted in the 45 amplifier I before being applied to the input electrodes of the tube II. This results in a linear relation between the applied modulating potentials and the amplitude of the modulated carrier in the output electrodes of tube 2. 50

Figure 2 shows two curves $J_a=f(e_{gm})$ and $J_a=f(e_1)$. J_a represents the amplitude of the modulated oscillations appearing in the output of the thermionic tube II. e_1 represents signal voltages with which the radio frequency os- 55

cillations are to be modulated. The curve $J_a=f(e_1)$ (function of e_1) represents the desired relation between the potential e_1 applied to the input circuit of amplifier I plotted against the 5 amplitude of the oscillations appearing in the output of tube 2. This relation would not be obtained in usual practice due to distortion in the modulation action. Applicant's novel distorting means may be used to correct the distortion which inherently results as described above. The line $J_a=f(e_{gm})$ of Fig. 2 represents the voltage e_{gm} resulting from the distortion of the voltage appearing in the output circuit of I when voltage e_1 is applied to the input, plotted 10 against the amplitude of the oscillations appearing in the output circuit of tube 2. This relation is as shown non-linear. The non-linear relation is of a sense such as to oppose the distortion accomplished during modulation and is 15 sufficient to compensate such distortion to the desired degree. These curves have been plotted on the basis of experimental data. It will be seen that $J_a=f(e_1)$ is practically rectilinear. The shape of this curve is governed directly by 20 the proper choice of the plate resistance. The voltage divider, the grid biasing potential, and the plate resistance of tube I serve to adapt this 25 tube to the given curve $J_a=f(e_{gm})$.

The tube I with appropriate associated network such as shown in Figure 1, can be used 30 for elimination of distortion in all cases where the I_a-e_{gm} characteristic shows appreciable unilateral curvature for the upper range of I_a (I_a —antenna current) values. A curve of 35 this type is illustrated in Figure 3. Modulation characteristics of the type shown in Figure 3 are encountered if e_{gm} is applied to the grid of a driver tube which works into a Class B or Class C power output stage. 40 The same type of I_a-e_{gm} characteristic is also encountered when using the modulation method which involves working on or varying the grid direct current in the modulated stage.

Figure 4 illustrates a modified form of applicant's novel modulation frequency amplifying and distorting means of Figure 1. In this arrangement, as will be seen, the cathode of the tube I is grounded through the distorting resistance e_r . In other respects this arrangement 45 is similar to the arrangement of Figure 1. The elements shown in Figure 4 may be substituted for the corresponding elements in Figure 1. This may be accomplished by merely breaking the circuits of Figure 1 at the point XY and 50 connecting the circuit of Figure 4 to the input of tube II. The circuit arrangement of Figure 4 is especially applicable to modulating schemes in which Heising modulation is used and when so applied the output of tube II is connected 55 to the plate circuit of tube 2 in a well known manner rather than to the grid circuit as in Figure 1.

In Figure 5 has been shown a further modification of the arrangement of Figure 1. In this modification the distorting resistance e_r is connected between the cathode of tube I and a point on the resistance 1. This modulation frequency amplifying and distorting means may be connected with the input circuit of any direct 60 current modulated oscillations relay or generator by merely connecting the circuit of Figure 5 to the input circuit at the points X and Y. The arrangement of Figure 5 is particularly adaptable to use in circuits where the grid bias of 65

the modulated tube II is controlled in accordance with the corrected modulating potentials.

When dealing with a characteristic curve having a knee at both ends, as shown in Figure 6, a circuit arrangement including two tubes, connected as shown in Figure 7, may be used. As will be seen by inspection of this arrangement, the distorting resistance e_r is connected in the lead connecting the cathodes of tubes I and I' so that the distorting resistance is common to 10 circuits of both tubes. This modification and operation is otherwise similar to the operation of the modulation frequency amplifying and distorting means described hereinbefore and a detailed description of said operation is thought 15 unnecessary. It will be noted, however, that this unit may be connected to any modulating scheme by merely connecting the points X and Y into the modulating circuit as described hereinbefore.

Having thus described my invention, I claim: 20

1. In a signalling system, a carrier frequency thermionic relay, a thermionic modulator having its anode to cathode impedance connected between the input electrodes of said relay, a modulation frequency amplifier, a resistance and a source 25 of potential connected in series between the input electrodes of said amplifier, means for applying a modulating potential across said resistance, a low impedance connection between the input circuit of said relay and said resistance, a 30 resistance and a source of potential connected directly between the output electrodes of said amplifier, and a connection between one terminal of said last named resistance and the control electrode of said modulator tube. 35

2. In a signalling system, a thermionic relay, a source of carrier frequency energy, means for connecting the input circuit of said relay with said source, a modulator tube having its anode to cathode impedance connected in series with 40 the input electrodes of said relay, a capacity in parallel with said impedance, a source of modulating signals, a modulating signal amplifier, a resistance connected with said source of modulating signals, means for connecting said resistance between the input electrodes of said modulating signal amplifier, a direct current connection between a point on said resistance and the control electrode of said relay, a resistance and a potential source connected directly between the output electrodes of said amplifier, and a connection between 45 said last named resistance and the control electrode of said modulator tube.

3. Means for modulating high frequency oscillations and for preventing distortion of the modulated signal which normally takes place when a high degree of modulation is required including, a thermionic repeater having a control electrode, a cathode and an input circuit connected therebetween and energized by wave energy of carrier 50 frequency, a modulator tube connected with the input circuit of said repeater, a source of modulating frequency, a modulating frequency amplifier, a resistance connecting said modulating frequency source to the input electrodes of said amplifier, a connection between a point on said resistance and the control electrode of said repeater, a connection between the output circuit of said amplifier and the control grid of said modulator tube, and means for distorting the voice frequencies repeated in said amplifier including a 55 resistance and a source of potential in the output circuit of said amplifier.

4. In a system for producing an alternating current of an amplitude varying in accordance 70 75

- with a controlling undulatory potential, a source of undulatory control potentials, an alternating current repeater tube on which alternating current may be impressed, means coupling said source and said current repeater tube together to modulate one current by the other current whereby the amplitude of the said alternating current energy in said repeater varies in accordance with the amplitude of the undulatory control potentials, and means interposed between said undulatory control potential source and said repeater, for altering the wave form of said control potentials as a function of the amplitude thereof whereby the amplitude of said alternating current energy in said repeater varies in substantially linear relation with respect to the amplitude of said controlling potential despite distortion which normally takes place in said repeater during such operation.
5. In apparatus for producing linear modulation of oscillations, an oscillation repeater comprising an electron discharge device having within an hermetically sealed container an electron emitting cathode and a control electrode, means for applying oscillations to be modulated to said device, a source of controlling potentials of varying amplitude, and a non-linear circuit, the amplitude of the potentials at the output of which vary non-linearly in accordance with the input 30 potentials, coupling said controlling potential source to the control electrode of said oscillation repeater whereby a characteristic of the oscillations repeated by said oscillation repeater varies linearly in response to the variations in potential 35 of the controlling potentials.
6. In apparatus of the character described, a carrier frequency wave repeater comprising, an electron discharge device having with an hermetically sealed container a cathode, and a control electrode, a circuit for applying carrier frequency waves to said control electrode, a source of modulating potentials, a thermionic amplifier having its input electrodes connected with said source of modulating potentials, and a circuit 40 including a resistance, the drop of potential through which is non-linear with respect to the amplitude of the modulating potentials, coupling the output electrodes of said amplifier to the control electrode of said carrier wave repeater, 45 whereby the oscillations produced by said oscillator vary linearly in response to the amplitude of the controlling potentials.
7. In a system for producing linear modulation of a high degree in a carrier wave, a thermionic tube having electrodes including an anode, a control grid and a cathode, circuits for applying the carrier wave to be modulated between the control grid and cathode of said tube, an output circuit connected between the anode and cathode of 50 said tube, a modulator tube having an anode, a cathode and a control grid, a circuit connecting the anode to cathode impedance of said modulator tube between two electrodes of said first named tube, a source of modulating potential, a 55 modulation frequency amplifier tube having anode, cathode and control grid, a circuit connected

between said source of modulating potentials and the control grid and cathode of said modulation frequency amplifier tube, an impedance in a circuit between the anode and cathode of said modulation frequency amplifier tube, and a connection between a point on said last named circuit and the control grid of said modulator tube and between the cathode of said modulator tube, and a point on the circuit between said source of modulating potentials and the control grid 10 and cathode of said modulation frequency amplifier tube.

8. In a signaling system, a thermionic tube having an anode, a cathode and a control grid, a circuit to be energized by carrier waves to be 15 modulated coupled to the control grid and cathode of said tube, an alternating current circuit connected to the anode and cathode of said tube, a modulator tube having an anode, a cathode and a control grid, a circuit coupling the anode and 20 cathode of said modulator tube to the cathode and one of the other electrodes of said thermionic tube, a source of modulating potentials, a first circuit connecting said source of modulating potentials to the control grid and cathode of said modulator tube for applying thereto modulating potentials, a second circuit, having a portion in common with said first circuit, connecting said source of modulating potentials to the control 25 grid and cathode of said modulator tube to apply thereto a supplemental modulating potential, and means in said second circuit for modifying the wave form of the supplemental modulating potential as a function of the amplitude of the 30 modulating potentials from said source.

9. A signaling system as recited in claim 8 in which said second circuit comprises an amplifier tube having an anode, a cathode and a control grid, said tube having its control grid and cathode connected to said source of modulating 40 potentials and a resistance connecting its anode to its cathode and a connection between its anode and the control grid of said modulator tube.

10. In a signaling system, a thermionic tube having an anode, a cathode and a control grid, 45 a circuit to be energized by carrier waves to be modulated coupled to the control grid and cathode of said tube, an alternating current circuit coupled to the anode and cathode of said tube, a modulator tube having an anode, a cathode 50 and a control grid, a circuit coupling the anode and cathode of said modulator tube to the cathode and control grid of said thermionic tube, a source of modulating potentials, a first impedance connected therewith, a first circuit connecting a portion of said first impedance to the control grid and cathode of said modulator tube, a second impedance in said first circuit, a thermionic amplifier tube having an anode, a cathode 55 and a control grid, a circuit connecting the anode and cathode of said thermionic amplifier tube to said second impedance, and a circuit connecting the control grid and cathode of said amplifier tube to said first named impedance.

HANS RODER.
